UNITED STATES PATENT OFFICE

100,834

DESIGN FOR A RADIO CABINET

Leslie C. Ruska, Cicero, Ill.

Application June 10, 1936, Serial No. 63,213

Term of patent 3½ years

To all whom it may concern:

Be it known that I, Leslie C. Ruska, a citizen of the United States of America, residing at Cicero, in the county of Cook and State of Illinois, have invented a new, original, and ornamental Design for a Radio Cabinet, of which the following is a specification, reference being had to the accompanying drawing, forming part thereof.

Fig. 1 is a front elevational view of a radio cabinet showing my new design.

Fig. 2 is a side elevation, and

Fig. 3 is a top plan view thereof.

I claim:

The ornamental design for a radio cabinet, as shown.

LESLIE C. RUSKA.
